CLAIM

The ornamental design for a humidifier, as shown and described.

DESCRIPTION

FIG. 1 is a top, front and left side perspective view of humidifier, showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and,
FIG. 7 is a bottom plan view thereof.
The broken lines in the drawings illustrate the portions of the humidifier, which form no part of the claimed design.
